UNITED STATES PATENT OFFICE.

GEORGE T. DEMARY, OF BOSTON, MASSACHUSETTS, ASSIGNOR TO THE NATIONAL HEELING MACHINE COMPANY, OF SAME PLACE.

HEEL-ATTACHING MACHINE.

SPECIFICATION forming part of Letters Patent No. 320,050, dated June 16, 1885.

Application filed January 23, 1885. (No model.)

To all whom it may concern:

Be it known that I, GEORGE T. DEMARY, of Boston, in the county of Suffolk and State of Massachusetts, a citizen of the United States, 5 have invented a new and useful Improvement in Heel-Attaching Machines, of which the following is a full, clear, and exact description, reference being had to the accompanying drawings, forming a part of this specification, in 10 explaining its nature.

The invention as represented is especially adapted for use in nailing what are technically known as "spring-heels"—that is, a heel made by forming down the outsole and interposing 15 between it at the heel end of the upper and insole one or more wedge-shaped lifts. It is necessary for nailing this work, first, that the points of the nails should converge in order that the heads may be driven as near the outer 20 line and edge of the sole as is desirable or practical, and that the points should be clinched upon the iron surface of the heel support. It is also desirable that headed nails be used for securing the parts together.

25 Referring to the drawings, Figure 1 is a view of an awl-holding block reversed, with the awls projecting therefrom. Fig. 2 is an elevation, enlarged, of the awl which I prefer to use. Fig. 3 is a perspective view, also enlarged, of the awl. Fig. 4 represents the templet-plate bearing upon the heel-section of a spring-heel boot or shoe and the awls in position above it. Fig. 5 is a view of the templet bearing upon the heel portion of the spring- 30 heel boot after the awls have been driven and nails fed, showing the holes pricked by the awl and the drivers in position. Fig. 6 represents the nails as having been driven by the drivers. Fig. 7 shows in elevation a boot or 35 shoe with the spring-heel, and Fig. 8 a view of a nail.

The heel-support *a* is much like that of the ordinary heel-support of the heel-attaching machines known in the market as the "National Heeling-Machine." The templet or 45 pressure plate *b* is made slightly concave upon its under surface, *b'*, and is provided with holes *b''*, considerably larger than the diameter of the awls used. The awls *c* are held by the awl-block, which is reciprocated in any desired 50 way; but I prefer that described in the Hen-

derson patents, Nos. 252,215 and 259,687. Each awl is made with one straight side, *c'*, and with a somewhat long, rounded, tapering point, *c''*, the taper being upon all sides excepting the 55 straight, the point of that portion being round, or very nearly round, and the point of course being out of line with the center. These awls are arranged in the awl-holder plate, so that their straight surfaces are upon the inside and 60 their inclined surfaces upon the outside, as by so doing the awls upon entering the leather are caused to take a downward and inward converging movement simultaneously, and the 65 nails which are inserted into said holes will be caused to take the same direction.

It will be apparent, on examination of the spring-heel shoe shown in Figs. 6 and 7, that the heel portion of the outsole, which forms the lower tread of the heel, instead of being 70 less in size than the insole, as is the case with the ordinary top lift of a heel, is considerably larger, and that it extends outwardly on all sides therefrom. It will also be observed that it is very considerably rounded, and that 75 in order to hold down the edge of the sole and fasten it securely to the insole it is necessary for the nails to extend inward, for if they were driven straight they would not enter the insole unless placed at such distance in from the 80 edge that the heel portion of the outsole would be of very little assistance in holding the edge well down and the remainder of the heel well compacted.

The nail-holder *d* has holes *d'* sufficiently 85 large to receive the headed nails which are used, and the drivers *e* are made larger than are ordinarily employed, in order to well cover the heads of the nails.

In operation the boot or shoe is placed upon 90 the heel-support and moved into position, the templet-plate is moved down upon the same, and its concave portion bears upon the heel portion of the sole. The awls are then reciprocated and withdrawn, the nail-carrier moved, 95 and the nails deposited in the holes in the templet and the drivers reciprocated, driving the nails therefrom into the spring-heel in an inward diverging direction. The nail should have a clinching-point in order to clinch easily upon the surface of the heel-support.

I would say that the awls herein described

may be used, by a slight change in the arrangement, for nailing heels known as "ogee" or "French" heels, or that class of heels which have a comparatively small upper surface, requiring that the points of the nails diverge as they are driven, and this is done by simply turning the awls half around, so that the beveled surface shall be upon the inside instead of the outside of such awls, or as many of them as it is necessary to use for forming these outwardly-inclined holes. Of course the degree of the inclination may be varied by changing the degree of the slope of the point.

The awls may of course have a flat bevel instead of a round tapering one.

Having thus fully described my invention, I claim and desire to secure by Letters Patent of the United States—

1. The combination of the templet-plate *b*,

having the concave surface *b'*, holes *b²*, larger than the awls *c*, and said awls having points straight upon one line and inclined upon the other, all substantially as and for the purposes described.

2. The combination of a templet-plate having holes, a nail-holder having holes of a size larger than the awls *c*, to receive headed nails and to permit of their passage therethrough, a gang or group of reciprocating awls, *c*, and a gang or group of reciprocating drivers of about the size of the holes in the nail-holder and templet, all substantially as and for the purposes described.

GEORGE T. DEMARY.
